(57) **CLAIM**

The ornamental design for a marine type communication device, as shown and described.

DESCRIPTION

FIG. 1 is a top-rear perspective view of a marine type communication device;

FIG. 2 is a bottom-rear perspective view thereof;

FIG. 3 is a rear view thereof;

FIG. 4 is a front view thereof;

FIG. 5 is a top view thereof;

FIG. 6 is a bottom view thereof;

FIG. 7 is a right side view thereof; and

FIG. 8 is a left side view thereof.

The broken lines shown in the figures represent features that form no part of the claimed design.
